UNITED STATES PATENT OFFICE.

RUSSEL BIGELOW AND FRANK E. BIGELOW, OF VANWERT, OHIO.

CHAIR-TRUCK.

SPECIFICATION forming part of Letters Patent No. 695,368, dated March 11, 1902.

Application filed August 22, 1901. Serial No. 72,935. (No model.)

To all whom it may concern:

Be it known that we, RUSSEL BIGELOW and FRANK E. BIGELOW, citizens of the United States, residing at Vanwert, in the county of 5 Vanwert and State of Ohio, have made certain new and useful Improvements in Chair-Trucks, of which the following is a specification.

Our invention is an improvement in roller 10 attachments or wheel-supports for chairs, more especially rocking-chairs used by invalids.

The invention is a truck composed of two 15 wheels and two axle-sections which are adjustable lengthwise upon each other and provided with bends or depressions adjacent to the wheels for receiving the chair-rockers or other base portion of chairs.

The details of construction, arrangement, 20 and operation are as hereinafter described, reference being had to the accompanying drawings, in which—

Figure 1 is a perspective view illustrating the practical application and use of our invention. Fig. 2 is an enlarged perspective view of the truck. Fig. 3 is a vertical section on the line 3 3 of Fig. 2.

As shown in Fig. 2, the truck consists chiefly of two running or transporting wheels 30 A and two axle-sections B B'. The said axle-sections are lapped lengthwise one upon another and secured together by means of clamps or clips C, which are constructed of thin elastic metal having flanges through 35 which screw-bolts c are inserted, as shown. It is apparent that by this construction the two axle-sections B B' may be adjusted lengthwise one upon the other and may be secured in any adjustment by means of the clamps.

40 C. Adjacent to the wheel-journals the said axle-sections have downward bends or depressions B². The said bends B² are practically rectangular, and plates D are secured on the horizontal portions of the bends by 45 means of rivets or bolts, as shown. These plates are arc shape, being curved slightly, as shown in Fig. 3, to better adapt them to the rockers of a chair, as illustrated in Fig. 1.

In practical use the truck is employed as 50 follows: The chair to which the truck is to be applied is tilted forward and the operator pushes the truck forward with his foot be-

near the rockers and then allows the chair to fall backward, when it will rest upon and be supported by the plates D, as shown in 55 Fig. 1. While the truck is so placed the chair may be propelled at will, since the friction between the rockers and plates D is sufficient to prevent slipping or sliding of the rockers thereon.

In practice it is intended that the drop or bend of the axle-sections shall extend to within about seven-eighths of an inch of the floor. The said bends are also to be made of sufficient width to receive rockers of different 65 thicknesses. It is apparent that by means of the construction shown the truck may be adjusted for chairs having rockers arranged at any distance apart. While the truck is particularly adapted for use with rocking-chairs, 70 it is apparent that it may be applied or used with other chairs having bottom side rounds which are near the floor. The wheels A are preferably constructed similarly to those of the safety-bicycle, being provided with a rubber tread and a skeleton frame.

It will be noted that the axis of the axle-journals b is in a line slightly above the body of the axle-sections, whereby the bends B² will always tend to hang vertically and to 80 maintain their position better than if the journals were in line with the body of the axle-sections.

What we claim is—

1. A chair-truck having an axle formed of 85 two parts adapted to slide lengthwise upon each other, means for securing the parts of the axle together, the axle being depressed and thereby adapted for engagement with the base of a chair for supporting it in the manner described.

2. The improved truck comprising two 90 wheels, two axle-sections which are adjustable lengthwise upon each other, means for securing the axle-sections in any adjustment, 95 and the said sections having each a downward bend or depression adapted to receive the rockers or other base portion of a chair, substantially as shown and described.

3. The improved chair-truck comprising 100 two wheels, two axle-sections which are adjustable lengthwise upon each other, clips applied to the lapped portions of the axle-sections, means for clamping the said clips upon

the latter, the said sections having downward bends or depressions adjacent to the wheels, and plates secured in such depressions at right angles to the axis of the axle, substantially as shown and described.

4. The improved chair-truck composed of two wheels, two axle-sections whose inner portions are lapped one upon the other and adapted for lengthwise adjustment, two clips securing the lapped portions in any adjustment, the said sections having downward

bends provided with plates adapted to serve as rests or supports for chair-rockers, and the journals of the said sections being in line with each other above the central lapped portions, substantially as shown and described. 15
